APPARATUS FOR TREATING HYDROCARBON OILS

Filed July 22, 1925

UNITED STATES PATENT OFFICE.

JOSEPH B. WEAVER, OF CHICAGO, ILLINOIS, ASSIGNOR, BY MESNE ASSIGNMENTS, TO
GYRO PROCESS CORPORATION, A CORPORATION OF MICHIGAN.

APPARATUS FOR TREATING HYDROCARBON OILS.

Application filed July 22, 1925. Serial No. 45,365.

This invention relates to apparatus and process for treating hydrocarbon oils and refers more particularly to an improved apparatus and process for the production of low boiling point hydrocarbons suitable for use as motor fuel or the like. The apparatus, however, is not limited in certain of its aspects to the particular process mentioned nor is the process limited to the particular 10 apparatus shown and described as certain features of the apparatus and the process have more general application.

Among the objects of the invention are: to provide an improved apparatus and process for treating hydrocarbon oils in the vapor phase; to provide an improved apparatus and process wherein the heat necessary for the vapor phase treatment is economically employed; to provide an apparatus and process in which the hot gases coming from the treatment of the hydrocarbon oil in the vapor phase are utilized in the heating of the oil in the liquid phase and in general, to provide a more efficient 20 and economical apparatus and process for treating hydrocarbon oils.

The invention further resides in the use of the above-mentioned features in connection with apparatus and process which involves the use of steam and a suitable agent (which term is intended to cover either a catalytic 30 agent or a chemical reagent) and in such other steps and features of construction and arrangements and combinations of parts as will more fully hereinafter appear.

In the drawings:

Figure 1 is a diagrammatic elevational view partly in section of an apparatus embodying my invention, and

Figure 2 is a cross-sectional view through one of the pipes of the convertor.

In the drawings which illustrate diagrammatically an apparatus embodying my invention and one which is capable of carrying out my improved process, A designates a pipe still having an inlet A' and an outlet A² leading to an expander or expanding chamber B. The latter at its upper end is connected by the pipes B' to the inlet end of the convertor C and at its lower end the expander has a pipe B² through which the heavy residue or liquid hydrocarbons may be drawn off. Interposed in the pipe or line B' just before it reaches the convertor is a

steam inlet D through which steam under 55 pressure is forced, together with the vapors in the pipe B', into the convertor. The outlet end of the convertor C is connected with a jet condenser or tar leg E. At the upper end the jet condenser is provided with a 60 nozzle F to which the make-up stock is conducted through a pipe F' from the tank F². In its upper portion the jet condenser E has a pipe G leading to a fractionating or scrubbing tower H while at its lower end the jet condenser or tar leg E is provided with a conduit I running back to the inlet end A' of the pipe still A. The tower H also has at its lower end a conduit H' connecting with the conduit I, and at its upper end the 70 tower H is provided with a pipe J leading to a condenser L. The lower end of the latter is connected by a pipe L' to a decanter M. As the product from the condenser L contains both water and hydrocarbon in 75 liquid form and a fixed gas, the decanter is arranged to separate these in the following manner: At the lower end of the decanter there is a water leg pipe N for conducting away the condensed water and near the 80 upper end a pipe O for conducting away the resultant hydrocarbon oil product. The fixed gas is conducted off through the pipe O'.

In general, the construction of the convertor is as follows: The pipe B' which conducts the vapors from the expander B opens into the header C' of the convertor. This header is divided into upper and lower sections by the wall C² and is connected to a similar header C³ by means of pipes Q. The incoming vapors pass through the upper sets of pipes Q to the header C³ and back to the lower pipe C to the lower portion of the header C' from which they pass through the outlet C⁴ to the jet condenser or tar leg E. The openings Q' in the end of the pipes Q are made progressively smaller from the top toward the bottom so that the rate of flow through the top tubes is less than through 90 the bottom tubes. This results in the contents of the upper tubes being subjected to the heat for a longer time than the contents of the lower tubes and will equalize the heating effect due to the lower tubes being subjected to the higher heat. Other means may be employed for accomplishing this, for example, the cores of the agent may be made 95 100 105

in various cross-sections to limit the flow and produce the same result.

As shown in Figure 2 the convertor tubes Q are filled with the agent. This may be ferric oxid or other suitable substance. The ferric oxid or other agent is mixed in a plastic and formed in bars S which are substantially star-shaped in cross-section. The bars are preferably of less length than the tubes Q and each bar is offset as shown in Figure 2 so as to cause the vapors to more completely impinge against the agent. The vapors in place of passing through the agent, pass between the latter and the inner walls of the convertor tubes Q and absorb the heat directly from the walls.

Describing next in detail the jet condenser or tar leg E, the construction of the latter is as follows: The vapors passing from the convertor C are discharged into the first chamber of the jet condenser or tar leg E. At the upper end of this chamber is arranged the nozzle F which is adapted to spray the liquid make-up stock and commingle them with the vapors. This commingling is further assisted by the placing of metal jackstones T through which the commingled convertor vapors and make-up stock pass down to the chamber E² before reaching the discharge chamber E³ from which the vapors pass through the pipe J to the fractionator or scrubbing tower H.

The operation of the apparatus is best described in connection with the carrying out of an illustrative process. In this process the hydrocarbon to be treated is passed through the inlet A' to the pipe still A where it is raised to a temperature of approximately 700° F., which, however, may be varied according to the characteristics of the charging stock.

The heated oils then pass through the outlet pipe A² under some pressure, for example, 25 pounds per square inch where they are discharged into the expander B. Owing to the sudden release of the pressure, complete vaporization of the lighter ends takes place and the vapors pass through the pipe B' at approximately 600° F. to the inlet end of the convertor C. The heavy ends are drawn off through the pipe B², any desired gravity being obtained by regulating the degree of heating in the pipe still and the pressure in the expander. Just before reaching the convertor they are commingled with steam under pressure and the combined oil vapors and steam vapors are then subjected to the action of the agent in the convertor under temperature of about 1100° F. and are caused to take up a certain percentage of hydrogen from the steam.

In cooling the vapors down from the high temperature of the convertor to the desired temperature for the fractionating tower I provide means for preventing the appara-

tus from being rendered inoperative by carbon deposits. I have discovered that most of the carbon is deposited in cooling down from the convertor temperature of 1100° F. to a temperature of about 600° F. and that 70 on lowering the temperature below that point there is very little carbon deposit. This discovery is utilized in providing an additional step in the process whereby the vapors coming from the condenser are 75 caused to commingle in the tar leg E with the make-up stock from the tank F². In so doing, the vapors are cooled to a temperature of approximately 450° F. and the carbon is deposited in the liquid in the lower 80 portion of the tar leg chamber E². The carbon being deposited in the liquid can be conveniently removed at predetermined times when the liquid in the bottom of the tar leg E² becomes too thick. A suitable 85 clean-out door is provided in the tar leg for this purpose. In practice, it is found that it is not necessary to remove this liquid more than once in 48 hours.

The use of the make-up stock in the jet 90 condenser for cooling the vapors from the convertor performs another important function, namely, it permits the jet condenser to act as a topper or stripper for removing the gasoline content from the fresh stock of 95 hydrocarbon oil and also serves to dehydrate the make-up stock before it passes through the pipe I to the inlet A' of the still. It also permits of a control of the end point 100 of the vapors from the fractionating tower, to which the vapors pass from the jet condenser through the pipes G. The fractionating tower H may be of any well-known construction and in some instances a scrubbing tower may be substituted in place of 105 the fractionating tower. Such vapors as will vaporize at the desired temperature, for example, at approximately 437° F. or less, pass out of the fractionating or scrubbing tower H through the pipe J to the condenser 110 L while higher boiling point fractions are returned through the pipe H' and the pipe I to the still A for the purpose of further treatment. The oil and water vapors are then condensed in the usual manner in the 115 condenser L and separated as previously described in the decanter M.

From the description of the above process it is apparent that the temperature in the convertor necessary for the proper treatment of the hydrocarbon oil in the vapor phase is greatly in excess of that necessary in the pipe still A. An important feature of the present invention is the utilization of the waste heat from the convertor for heating the hydrocarbon oil in the pipe still A. As shown in Figure 1, the convertor C has a firebox R from which the gases pass up inwardly to traverse the convertor tubes Q and then pass downwardly on the opposite 120 125 130

side of the baffle R' to the outlet R². From here the products of combustion pass to the pipe still A where they are commingled with the burning gases from the firebox V and are forced by the baffles V' to traverse the tube of the pipe still before reaching the discharge stack V². The firebox V may be provided with a burner W which is adapted to utilize the fixed gases discharged from the pipe O' although any suitable burner and any suitable source of supply of fuel may be used for heating purposes. By the use of the novel apparatus above described it is possible to efficiently and economically treat hydrocarbon oils in the vapor phase at the extreme heat necessary for carrying on such treatment and to then utilize the products of combustion which have been employed for heating the convertor to also heat the oil in the liquid phase in the pipe still since the latter requires treatment at a lower temperature.

While I have shown and described diagrammatically one form of apparatus, the invention is not limited to the use of the particular apparatus described nor to its use in connection with the particular process as various changes both in the construction of the apparatus or process can be made within the scope of my invention.

What I claim as my invention is:

1. In apparatus for treating hydrocarbon oil, the combination with a pipe still in which the oil is subjected to heat while in a liquid phase, of an expander in which the oil from the still is permitted to expand, of a convertor in which the vapors from the expander are subjected to a conversion action while in the vapor phase, means for heating the vapors in the convertor to a temperature in excess of approximately 1000° F. and means for utilizing the same products of combustion which are used to heat the vapors in the convertor at a high temperature for

heating the oil in the still at a lower temperature.

2. In apparatus for treating hydrocarbon oil, the combination with a pipe still in which the oil is subjected to heat while in the liquid phase, an expander in which the oil from the pipe still is permitted to expand into the vapor phase, a convertor in which the vapors from the expander are subjected to a conversion action while in the vapor phase, a tar leg into which the vapors from the convertor pass, a fractionating or scrubbing tower in which the uncondensed vapors pass from the tar leg, connections between said still and expander, expander and convertor, convertor and tar leg, tar leg and tower, and a lead from said tower and from said tar leg whereby the heavier products in both are conducted back to the pipe still.

3. In apparatus for treating hydrocarbon oil, the combination with a pipe still in which the oil is subjected to heat while in the liquid phase, an expander in which the oil from the pipe still is permitted to expand into the vapor phase, a convertor in which the vapors from the expander are subjected to a conversion action while in the vapor phase, a tar leg into which the vapors from the convertor pass, a fractionating or scrubbing tower in which the uncondensed vapors pass from the tar leg, connections between said still and expander, expander and convertor, convertor and tar leg, tar leg and tower, and a lead from said tower and from said tar leg whereby the heavier products in both are conducted back to the pipe still, means for heating the vapors in the convertor to a temperature in excess of approximately 1000° F. and means for utilizing the same products of combustion for heating the oil in the still at a lower temperature.

In testimony whereof I affix my signature.
